(57) **ABSTRACT**

An electrical connector for connecting first and second conductive crossing bars together comprising a first elongated enclosure for at least partially enclosing the first bar; and a second elongated enclosure intersecting said first elongated enclosure for at least partially enclosing the second bar. The first and second enclosures are comprised of a single sheet metal member. The first elongated enclosure may be crimped on the first bar and the second elongated enclosure may be separately crimped on the second bar.

FIG. 1

FIG. 2

FIG. 3

FIG. 4

FIG. 2A

ELECTRICAL CONNECTOR FOR CROSSING REINFORCING BARS

BACKGROUND OF THE INVENTION

1. Field of the Invention

The present invention relates to electrical connectors and, more particularly, to a connector for reinforcing bars which are crossing each other.

2. Prior Art

U.S. Pat. No. 2,760,798 discloses an electrical tap connector formed from a blank of sheet metal. The connector is for connecting two crossing conductors. The connector is compressed onto the two conductors simultaneously. In the prior art, crossing reinforcing bars, such as used in steel reinforced concrete, were electrically connected to each other by arc welding the two bars to each other for electrical bonding. It is desired to eliminate the need for welding reinforcing bars to each other.

SUMMARY OF THE INVENTION

In accordance with one embodiment of the present invention, an electrical connector is provided for connecting first and second conductive crossing bars together comprising a first elongated enclosure for at least partially enclosing the first bar; and a second elongated enclosure intersecting said first elongated enclosure for at least partially enclosing the second bar. The first and second enclosures are comprised of a single sheet metal member. The first elongated enclosure may be crimped on the first bar and the second elongated enclosure may be separately crimped on the second bar.

In accordance with another embodiment of the present invention, an electrical connector is provided comprising a first section having a first receiving area which is sized and shaped to receive a portion of a first elongate bar therein; and a second section having a second receiving area which is sized and shaped to receive a portion of a second elongate bar therein. The first and second sections are comprised of a single sheet metal member. The first and second receiving areas are angled relative to each other. The receiving areas are connected to each other at an intersection of the receiving areas such that the first and second bars contact each other when located in the receiving areas.

In accordance with one method of the present invention, a method of connecting two bars with an electrical connector is provided comprising steps of providing the electrical connector with two bar receiving areas located at angles relative to each other, the connector comprising a formed sheet metal member; locating the electrical connector on the two bars, the two bars being angled relative to each other; and compressing the electrical connector onto the bars by compressing a first section of the connector onto a first one of the bars and subsequently compressing a second separate section of the connector onto a second one of the bar.

BRIEF DESCRIPTION OF THE DRAWINGS

The foregoing aspects and other features of the present invention are explained in the following description, taken in connection with the accompanying drawings, wherein:

FIG. 1 is an exploded perspective view of two crossing bars and an electrical connector incorporating features of the present invention;

FIG. 2 is a perspective view of an alternate embodiment of the present invention;

FIG. 2A is a top plan view of a flat sheet metal blank used to manufacture the connector shown in FIG. 2;

FIG. 3 is a perspective view of another alternate embodiment of the present invention; and

FIG. 4 is a perspective view of another alternate embodiment of the present invention.

DETAILED DESCRIPTION OF THE PREFERRED EMBODIMENT

Referring to FIG. 1, there is shown an exploded perspective view of an electrical connector 10 incorporating features of the present invention and two crossing bars A, B intended to be connected by the connector. Although the present invention will be described with reference to the embodiments shown in the drawings, it should be understood that the present invention can be embodied in many alternate forms of embodiments. In addition, any suitable size, shape or type of elements or materials could be used.

The connector 10 is preferably a one-piece member comprised of stamped sheet metal. However, in alternate embodiments, the connector could be comprised of multiple members. Any suitable material other than sheet metal could also be used. Any suitable method(s) could be used to form the connector other than or in addition to stamping. The bars A, B are preferably steel reinforcing bars, such as those used in steel reinforced concrete construction. However, the connector 10 could be used to electrically connect any suitable crossing elongate members, such as connecting crossing electrical ground cables to each other or connecting a ground cable to a crossing reinforcing bar.

The connector 10 generally comprises a first section 12 and a second section 14. The first section 12 forms a first generally elongate enclosure with a first receiving area 16. The second section 14 forms a second generally elongate enclosure with a second receiving area 18. The first receiving area 16 is suitably sized and shaped to receive a portion of the first bar A therein. The second receiving area 18 is suitably sized and shaped to receive a portion of the second bar B therein. The two receiving areas 16, 18 are generally perpendicular to each other, slightly offset vertically from each other, but intersect or are adjacent to each other. In alternate embodiments any suitable angle other than 90° could be provided between the receiving areas 16, 18. In addition, the receiving areas need not be adjacent or intersect each other.

In this embodiment the second section 14 generally comprises two portions 20, 22. Each portion 20, 22 is located on opposite sides of the first section 12. The two portions 20, 22 are substantially mirror images of each other. However, in alternate embodiments the portions could have different sizes or shapes. In addition, the second section could be comprised of more or less than two portions. In this embodiment each portion 20, 22 has a general cross-sectional "C" shape. However, any suitable cross-sectional shape(s) could be provided. In this embodiment the cross-sectional "C" shape provides an entrance 24 into the receiving area 18 between the two elongate ends 26, 28 at a bottom side of the connector 10. In an alternate embodiment the entrance or entrances into the second receiving area 18 could be provided on any suitable side(s). The entrance 24 is preferably larger than the diameter of the bar B such that the connector can be slipped onto the bar B via the entrance 24. However, in alternate embodiments the entrance 24 need not be provided, such as when the connector is longitudinally slid onto the bar B. Alternatively, the entrance 24 could be slightly smaller than the diameter of the bar B such that the

connector **10** is snapped onto the bar **B** with the ends **26, 28** resiliently moving as the bar **B** passes through the entrance **24**. Thus, the connector **10** can be retained with the bar **B** as a loose pre-connection retainment before final connection of the connector to the bar **B**.

The first section **12** has an entrance **30** between two ends **32, 34** at the bottom side of the connector **10**. However, the entrance could be provided on any suitable side. The entrance **30** is preferably larger than the diameter of the bar **A** such that the connector **10** can be slipped onto the bar **A** via the entrance **30**. In an alternate embodiment the width of the entrance **30** could be slightly smaller than the diameter of the bar **A** such that the bar **A** must be snapped through the entrance **30**. The ends **32, 34** can then prevent the bar **A** from inadvertently exiting the connector through the entrance **30**; forming a loose pre-connection retainment before final connection of the connector to the bar **A**. In this embodiment the two entrances **24, 30** intersect each other at the bottom side of the connector. Thus, when both bars **A, B** are being located into their respective receiving areas **16, 18** via the entrances **30, 24**, the first bar **A** must first be positioned in its receiving area **16** before the second bar **B** is positioned in its receiving area. Otherwise, the second bar **B** would block the entrance **30** to prevent the first bar **A** from entering the first receiving area **16** through the entrance **30**. The first section **12** has a general elongate shape extending outward from opposite sides of the second section. Thus, the connector forms a general "X" shaped profile. In an alternate embodiment, the first section **12** need not extend outward from both opposite lateral sides of the second section. One or both of the opposite ends of the first section **12** could be flush with the lateral sides of the second section or could be recessed inward from the lateral sides of the second section.

With the two bars **A, B** crossing each other as shown in FIG. 1, the connector **10** can merely be placed onto the two bars in direction **C** onto the bars' intersection or crossing. With this embodiment the first bar **A** is captured between the top of the first section **12** and the top of the second bar **B**. Therefore, the first section **12** does not need to be crimped onto the first bar **A**. Instead, only the second section **14** is crimped. More specifically, the two portions **20, 22** are separately crimped onto the second bar **B** on opposite lateral sides of the first bar **A**. A suitable type of crimping or compression tool could be used, such as disclosed in U.S. Pat. Nos. 5,062,290 and 4,942,757 which are hereby incorporated by reference in their entirities. In an alternate embodiment the first section **12** could also be crimped onto the first bar **A**. When the two portions **20, 22** are crimped onto the second bar **B**, the top of the first section **12** compresses the first bar **A** against the second bar **B**. This forms a stationary fixed mechanical connection of the two bars **A, B** by the connector **10**. Contact directly between the two bars **A, B** at their intersection and by the connector **10** on the two bars forms an electrical connection between the two bars.

Referring now to FIG. 2 an alternate embodiment of the connector will be described. In this embodiment the connector **50** generally comprises two sections **52, 54** generally crossing each other, each having an elongate conductor or bar receiving area **56, 58**, entrances **60, 62** on a same side into the receiving areas, and one section **52** being interposed between two portions **64, 66** of the other section **54**. In this embodiment the first section **52** has general square cross-sectional shapes at two end portions **68, 69** (with one open corner to form parts of the entrance **60**) and a center portion **70** with a general angled roof cross-section shape. The portions **64, 66** of the second section **54** also have a general

square cross-sectional shape with one open corner to form parts of the entrance **62**. With this embodiment the connector **50** is preferably directly crimped to both bars **A, B**. More specifically, the two portions **64, 66** are both crimped to the second bar **B** and the two portions **68, 69** are both crimped to the first bar **A**. However, in an alternate method only one of the portions **64** or **66** need to be compressed onto the second bar **B** and/or only one of the portions **68** or **69** need be compressed onto the first bar **A**. FIG. 2A shows a flat sheet metal blank **50'** which is used to form the connector **50** shown in FIG. 2. The blank **50'** is cut at locations **S**. This forms locations **64', 66', 68', 69', 70'** which can then be stamped or bent at the dashed lines to form the portions **64, 66, 68, 69, 70**.

Referring now to FIG. 3, another alternate embodiment is shown. In this embodiment the connector **80** is preferably comprised of a one-piece formed sheet metal member with a first section **82** and an integral second section **84**. In this embodiment the connector has a general "T" shaped profile. However, any suitable profile could be provided. The first section **82** has a general C-shaped cross-section forming a first receiving area **86**. The second section **84** has a general C-shaped cross-section forming a second receiving area **88**. The first section **82** extends from an end of the second section **84**. The first section **82** is generally perpendicular to the second section **84**. The two receiving areas **86, 88** are generally perpendicular to each other, but spaced from each other with a portion of the sheet metal member separating the two areas **86, 88**. The entrance **90** into the first section **82** is separate and spaced from the entrance **92** into the second section **84**. The two entrances **90, 92** are also on different sides of the connector **80**. FIG. 4 illustrates another alternate embodiment similar to FIG. 3, but wherein the two receiving areas **106, 108** formed by the two sections **102, 104** slightly intersect. The first and second bars **A, B** would contact each other with the use of this embodiment.

It should be understood that the foregoing description is only illustrative of the invention. Various alternatives and modifications can be devised by those skilled in the art without departing from the invention. Accordingly, the present invention is intended to embrace all such alternatives, modifications and variances which fall within the scope of the appended claims.

What is claimed is:

- An electrical connector for connecting first and second conductive crossing bars together comprising:
  - a first elongated enclosure for at least partially enclosing the first bar; and
  - a second elongated enclosure intersecting said first elongated enclosure for at least partially enclosing the second bar

wherein the first and second enclosures are comprised of a single sheet metal member, wherein the first elongated enclosure may be crimped on the first bar and the second elongated enclosure may be separately crimped on the second bar, and wherein an entrance for the first bar into the first enclosure passes through a portion of an entrance for the second bar into the second enclosure.
- An electrical connector as in claim 1 wherein an entrance for the first bar into the first enclosure is on a same side of the connector as an entrance for the second bar into the second enclosure.
- An electrical connector as in claim 1 wherein the first and second enclosures are generally angled relative to each other.

4. An electrical connector as in claim 1 wherein the connector comprises a general "X" shaped profile.
5. An electrical connector for connecting first and second conductive crossing bars together comprising:
- a first elongated enclosure for at least partially enclosing the first bar; and
  - a second elongated enclosure intersecting said first elongated enclosure for at least partially enclosing the second bar;
- wherein the first and second enclosures are comprised of a single sheet metal member, wherein the first elongated enclosure may be crimped on the first bar and the second elongated enclosure may be separately crimped on the second bar, wherein the connector comprises a general "T" shaped profile, and wherein a portion of the sheet metal member separates bar receiving areas formed by the first and second enclosures from each other.
6. An electrical connector comprising:
- a first section having a first receiving area which is sized and shaped to receive a portion of a first elongate bar therein; and
  - a second section having a second receiving area which is sized and shaped to receive a portion of a second elongate bar therein,
- wherein the first and second sections are comprised of a single sheet metal member, wherein the first and second receiving areas are angled relative to each other, wherein the receiving areas are connected to each other at an intersection of the receiving areas such that the first and second bars contact each other when located in the receiving areas, and wherein an entrance for the portion of the first bar into the first section is on a same

10 side of the connector as an entrance for the portion of the second bar into the second section.

7. An electrical connector as in claim 6 wherein the first and second sections each have a general elongate shape.

8. An electrical connector as in claim 6 wherein the first and second sections form a general "X" shaped profile.

9. An electrical connector as in claim 6 wherein the first and second sections form a general "T" shaped profile.

10. An electrical connector as in claim 6 wherein an entrance for the first bar into the first receiving area passes through a portion of an entrance for the second bar into the second receiving area.

11. An electrical connector as in claim 6 wherein each section comprises two spaced and separate respective compression areas.

12. A method of connecting two bars with an electrical connector comprising steps of:

providing the electrical connector with two bar receiving areas located at angles relative to each other, the connector comprising a formed sheet metal member, the connector having a first section and a second section which are sized and shaped to connect to the two bars at an overlapping X-shaped crossing area of the two bars;

locating the electrical connector on the two bars, the two bars being angled relative to each other; and compressing the electrical connector onto the bars by compressing the first section of the connector onto a first one of the bars and subsequently separately compressing the second separate section of the connector onto a second one of the bar.
